United States Patent Office

Des. 185,324
Patented May 26, 1959

185,324

FONT OF TYPE

Sheldon R. Shepard, New York, N.Y.

Application September 11, 1958, Serial No. 52,616

Term of patent 14 years

(Cl. D64—12)

Fig. 1 is a plan view of the capital letters of a font of type showing my new design;

Fig. 2 is a plan view of the complementary numerals; and

Fig. 3 is a plan view of the lower case letters thereof.

I claim:

The ornamental design for a font of type, substantially as shown.
